UNITED STATES PATENT OFFICE.

LOVELL T. RICHARDSON, OF AUBURN, NEW YORK.

IMPROVEMENT IN DIES FOR FORGING HOE-PLATES.

Specification forming part of Letters Patent No. 136,672, dated March 11, 1873.

To all whom it may concern:

Be it known that I, LOVELL T. RICHARDSON, of Auburn, in the county of Cayuga and State of New York, have invented a new and useful Improvement in Dies for Plating Planters' Hoes, of which the following is a specification:

This invention relates to dies which are used in steam, water, or other power hammers for plating planters' hoes from the blanks before they are rolled out; and consists in the construction and arrangement of the dies by means of which the operation of plating is greatly facilitated. It also consists in the plate prepared thereby.

In the accompanying drawing, Figure 1 represents a vertical section of the two dies taken on the line $x x$ of Fig. 2. Fig. 2 is a side view. Fig. 3 is a face view of the upper or hammer die. Fig. 4 is a face view of the lower or bed die. Fig. 5 represents the blank from which the hoe is made. Fig. 6 is a plate which has been operated upon by the dies and made ready for the rollers.

Similar letters of reference indicate corresponding parts.

A is the hammer-head to which the upper die is secured by means of the key B. C is the block or bed in which the lower die is secured by the key D. E is the upper die, and F is the lower die.

The face of the lower die, from the point G, is the arc of a circle transversely, as seen in Fig. 1. The portion H of this die (one-fourth of its length, more or less) is a flat or plane surface. The face of the upper die E is beveled on its corners so as to leave a flat tapering surface, I, as seen in Fig. 3. Dies of this form are better adapted for plating planters' hoes than any hitherto used. They belong to a class of dies which are known in the business as "gage-dies," but differ in their construction from any gage-dies in use.

The operation of plating hoes is greatly facilitated, and much valuable time is saved by their use.

J is a plate prepared by these dies. K is the rib formed on the face of the plate.

Having thus described my invention, I claim as new and desire to secure by Letters Patent—

The dies E and F, constructed and arranged, substantially as shown and described, for plating planters' hoes as specified.

LOVELL T. RICHARDSON.
